AUSTEN M. CURTIS, OF EAST ORANGE, NEW JERSEY, ASSIGNOR TO WESTERN ELECTRIC COMPANY, INCORPORATED, OF NEW YORK, N. Y., A CORPORATION OF NEW YORK

SUBMARINE-SIGNALING SYSTEM

Application filed July 14, 1927. Serial No. 205,561.

This invention relates to submarine signaling systems and more particularly to those systems in which terminal equipment is designed to operate to permit the transmission of signals over a submarine cable at high speeds.

An object of the invention is to facilitate the adjustment of the very low frequency components of signals transmitted over a submarine cable and to thereby provide greater flexibility in shaping signals.

It is well known in the art that auxiliary apparatus designed to operate upon the wave form of the signals, may be employed at the terminal of a submarine cable to so shape these wave forms as to increase the legibility of the signals recorded at the terminal. This apparatus which is generally referred to as a shaping, or distortion-correcting network, 20 may be used in combination with both the sending and the receiving equipments, and such combinations used in connection with high speed signaling are disclosed in Patent No. 1,624,396 granted to A. M. Curtis on

25 April 12, 1927.

The circuits used at the sending terminal, and with which the present invention is particularly concerned, take the form of an impedance element which has a low value 30 as compared with the characteristic impedance of the cable and which is, in effect, a shunt path to earth on both the cable as viewed from the transmitter and on its associated transmitter and shunted sending condenser as viewed from the cable. At first a low resistance was employed alone in the shunt path to earth but it was found to have the disadvantage of shunting to earth the larger part of the extremely low frequency 35 components of the transmitted signals, thereby requiring that the receiving apparatus be adjusted to be rather sensitistive to these very low frequency signal components. This, in some cases, may cause an objectionable amount of "earth current" to flow thru the receiving networks. In a simplex operated submarine telegraph system the establishment of this earth current during the operation of switching from sending to receiving produces a heavy surge thru the ampli-

fier and this surge tends to momentarily displace the zero of the signal. Therefore, in order to reduce the strength of earth current and switching surges and to allow the use of a receiving shaping network which was relatively insensitive to currents of frequencies approaching direct current, a condenser of large capacity, that is, one of the order of several hundred microfarads, was inserted 55 in series with the low resistance element in the shunt path to earth. This condenser is of such capacity that it has little influence on the action of the earth path shunt resistance at any but the extremely low frequency 60 components of the signal.

According to the present invention a partial correction, or shaping, of the extremely low frequency components of the signal wave form is effected at the transmitting terminal, thereby reducing to a considerable degree the amount of correction which would otherwise 70 be necessary at the receiving terminal. This partial correction is made by connecting in shunt to the large capacity condenser a variable resistance element having a relatively 75 high value, and by a suitable adjustment of this variable resistance the frequency components ranging from zero to about 3 cycles a second, are offered a path of lower resistance than thru the high capacity condenser. 80 In this manner, the adjustment of the shape of the signals received, with regard to the very low frequency components which cause "zero wander" is greatly facilitated.

This invention will be better understood 85 by reference to the following detailed description taken in connection with the single figure of the accompanying drawing. In the drawing it will be noted that the equipment, shown in detail, is that required for transmitting signals from one end of a cable of a submarine telegraph system arranged for simplex operation. This equipment is somewhat similar to that shown in Fig. 11 of the Curtis Patent No. 1,624,396 to which reference has previously been made.

Referring to the drawing, a single core submarine cable 1 is terminated in a twin core section of submarine cable 2. One core 3 of the twin-core section is spliced at one

end to the single core cable 1 and at the other end is connected to a switch 4. The switch can be connected in its upper position to the signal receiving apparatus R and in its lower position to the transmitting equipment T, the individual elements of which will be hereinafter designated. The other core 5 of the twin-core section is connected at the sea end thru a resistance 6 to a conductor in contact with the sea water. In the particular arrangement shown the resistance is connected to the cable armor wires at point 7 and a conventional ground connection, shown by dotted lines, is used to indicate that the armor wires are grounded. The core 5, together with the network 6 grounded at the point 7, constitutes a cable-balancing return circuit. The shore end of core 5 is connected to the receiving apparatus R. A type of core suitable for both the single core cable 1 and twin core section 2 comprises a copper conductor provided with a wrapping of a magnetic material, such as the nickel-iron alloy, generally known in the art as "permalloy" and disclosed in Patent No. 1,586,884 granted to G. W. Elmen on June 1, 1926, which, by greatly increasing the inductance of the cable, permits it to be operated at a high signaling speed.

The transmitting equipment T comprises a positive and negative impulse transmitter 8, or the equivalent distributor when printing telegraph operation is desired, series resistance 9 of 10 to 50 ohms, and condenser 10 of 20 to 75 microfarads, with shunting resistance 11 of 5,000 to 100,000 ohms. As hereinbefore explained the transmitting equipment T may be connected to the core 3 of the twin-core section 2 by means of switch 4 in its lower position. One terminal of the transmitter equipment is then connected to the core 3, while the other terminal is grounded at an extra earth 12 at sea. Connected across the cable terminals is a low resistance shunt path comprising resistance 13 of 50 to 200 ohms and condenser 14 of several hundred microfarads in series, with a relatively high resistance 15 shunted across the condenser. Resistance 15 may range in magnitude from about one hundred ohms to many thousand ohms.

The characteristic impedance of cable 1 is approximately 400 ohms for voltages of the higher frequencies involved in signaling, but it is evident that for the voltages of very low frequencies this can not be the case. For example, at zero frequency, the characteristic impedance of the cable is its direct current resistance; and in the case of an actual cable between New York and the Azores, this resistance is about 4,600 ohms. At first, the principal difficulty in correcting the distortion of this cable for signaling speeds above 30 cycles a second, lay in reducing sufficiently the relatively enormous amount of signal-

ing components of the lower frequencies which are transmitted over the cable. This required the utilization to the fullest extent of shaping at both the transmitting and receiving terminals of the cable. The shunt resistance 13 added materially in accomplishing this result, but, as stated above, too great a part of the low frequency components of the transmitted signal, was shunted to earth. In order to reduce the amount of low frequency components flowing to earth thru resistance 13, condenser 14 was inserted in series with the shunt resistance 13, this condenser being so large that it has little influence on the action of the shunt resistance 13 at any but the extremely low frequency components of the signal. The distortion of the signal wave form produced by these extremely low frequency components had to be corrected by the shaping network at the receiving station. The addition of variable resistance 15 in shunt to condenser 14 permits the amplitude of the signal components of very low frequencies transmitted to the cable to be controlled at the sending station, thereby facilitating markedly the adjustment of the correcting networks at the receiving station.

What is claimed is:

1. A cable signaling system comprising a cable, means for impressing signaling current on said cable, a path connected in parallel with said cable as viewed from said means and having an impedance low in comparison with the characteristic impedance of the cable, said path being conductive to direct current but including a high resistance and a high capacity condenser for regulating the amount of the extremely low frequency components shunted to earth, whereby surges on the cable due to excessive low frequency components in the transmitted signal wave, are greatly reduced.

2. A cable signaling system comprising a cable, means for impressing a signaling current on said cable, a path connected in parallel with said cable as viewed from said means and having a low impedance for high frequencies in comparison to the characteristic impedance of the cable and a high resistance for the very low frequencies, said path comprising a low resistance element and a large condenser in series therewith, and a relatively high resistance in shunt to said condenser.

3. A cable signaling system comprising a cable, an impulse transmitter, a sending condenser connected between said transmitter and said cable, and a path to earth having an impedance low in comparison with the characteristic impedance of the cable, connected at a point between said cable and said condenser, said path comprising a low resistance and a large condenser in

series therewith, and a relatively high resistance in shunt to said large condenser.

4. In a cable signaling system, a cable, transmitting apparatus connected thereto comprising an impulse transmitter and a resistance shunted sending condenser connected in series therewith, and a series circuit connected in shunt to said cable as viewed from said transmitting apparatus, said circuit comprising a low resistance, a condenser so large that its effect upon the impedance of said series circuit except at very low frequencies is negligible, and a comparatively high resistance in shunt to said large condenser for overcoming the effects of said large condenser at the very low frequencies.

5. In a submarine cable signaling system, a submarine cable, signaling apparatus associated therewith, the characteristics of said cable and said apparatus being such that certain frequency components of the signaling current are transmitted thereover with less attenuation than are other frequency components, and a path to earth connected at a point between said signaling apparatus and said cable, said path comprising a low resistance and a large condenser, and an adjustable relatively high resistance in shunt to said large condenser.

6. A submarine cable signaling system comprising a submarine cable loaded with an alloy comprising nickel and iron having high permeability at low magnetizing forces, a sending condenser, an impulse transmitter connected to said cable thru said sending condenser, and a resistance path to earth connected between said cable and said condenser being of low value compared with the characteristic impedance of the cable, said path comprising a low resistance and a condenser so large that its effects on the low resistance except at very low frequencies is negligible, and a comparatively high resistance in shunt to said large condenser for overcoming the effect of said large condenser at the very low frequencies.

7. A cable signaling system comprising a cable, means for impressing signaling current on said cable, a path connected fixedly at a point between said means and said cable having an impedance which is low in comparison with the characteristic impedance of the cable, said path being conductive to direct current and including an adjustable high resistance and a high capacity condenser.

8. A cable signaling system comprising a cable, an impulse transmitter, a sending condenser connected between said transmitter and said cable, and a path to earth having an impedance which is low in comparison with the characteristic impedance of the cable and being fixedly connected at a point between said sending condenser and said cable, said path comprising a low resistance

and a large condenser in series therewith and an adjustable relatively high resistance in shunt with said large condenser.

In witness whereof, I hereunto subscribe my name this 12 day of July, A. D. 1927.

AUSTEN M. CURTIS.
